METAL MELTING FURNACE

Filip Tharaldsen, Oslo, Norway

Application December 13, 1937, Serial No. 179,557
In Norway December 21, 1936

2 Claims. (Cl. 91—12.5)

This invention relates to the art of melting zinc and other metals having low melting and ignition temperatures and more particularly to improved apparatus for reducing and maintaining the metals in the fluid state. The invention is especially suitable for application to galvanizing processes and, by way of example, it will be described in connection with such use.

Heretofore the general practice has been to place the zinc or other metal in iron or steel containers, commonly termed "kettles" and apply heat externally to the side walls of the containers. Although this method has the advantage of insuring a sufficiently high rate of heat transfer to keep the zinc or other metal in proper condition, the tendency of the zinc to amalgamate with the iron of the container results in rapid contamination of the pure zinc and premature failure of the kettle. The destructive action is accelerated by the presence of chlorides which are unavoidably introduced in minute quantities into the spelter or dross during the galvanizing process. Another method of heating and melting the metals utilizes a refractory lined container provided with recesses or grooves in its side walls in which are positioned heating coils of various types. Inasmuch as the coils are not in contact with the metal being heated, the difficulty of maintaining the required temperature within desired limits is great and frequent interruptions in the galvanizing process are experienced. Also the efficiency of the heating method is very low and the refractory materials are apt to fail because of localized high temperature zones and pronounced temperature gradients. In any event the life of the refractory materials is short, necessitating frequent rebuilding of the furnace.

In the melting of zinc, for example, it is necessary to use a temperature of about 930° F. in order to secure a reasonable rate of heat transmission. The heat lost by radiation of the comparatively large body of metal and by absorption by the sheets or wire being galvanized must be compensated for to maintain the zinc at the required temperature. At 930° temperature, however, zinc burns and consequently cannot be exposed to the air when such temperatures are reached. I overcome the above mentioned difficulties by providing a separate heating chamber above the surface of the zinc which chamber is sealed against the admission of air.

The apparatus of my invention utilizes a refractory lined container which increases the length of use of the device and aids in keeping

the metals low in impurities. Ordinarily, zinc in a galvanizing bath is contaminated by the zinc-iron alloy formed by the action of the zinc on the iron of the container and by similar action on the metal being galvanized. The elimination of the first source results in a correspondingly increased purity of the spelter and I have provided novel means and method of operation to alleviate the inherent objections to the contamination by the second source. In the galvanizing process, when the steel to be galvanized reaches a temperature higher than the fusion temperature of the zinc or spelter, a hard, brittle, iron-zinc alloy is formed, portions of which spawl off and mix with the spelter. The presence of this alloy, commonly termed "dross," is objectionable and must be removed from the spelter which contacts the material being processed. The dross and other impurities ordinarily of greater specific gravity than zinc will accumulate in the bath and will gravitate downwardly and be found at the lower or bottom part of the bath. In order to prevent an undue concentration of these impurities and to provide for a more economical operation of the process, I provide means whereby zinc containing a controlled amount of such impurities may be readily withdrawn from the bath, which zinc will not be below the recognized standard of purity for ordinary commercial zinc.

Pure electrolytic zinc which is produced commercially in large quantities at a price only slightly higher than ordinary commercial zinc, has an iron content of .005% or less and a lead content of .01% or less. Ordinary commercial zinc has an iron content of about .1% and lead content of about 1.5%. The ordinary grades are extensively used for castings and for the production of the poorer quality brasses. It is essential however that the zinc used for galvanizing purposes should be as pure as possible in order to obtain the best physical and chemical properties in the finished product. The use of my method enables the impurities to be drawn off in commercially valuable form, i. e., in zinc having an iron content of approximately .1% whereas in the methods customarily employed about 10% of the zinc is lost in dross, which substance has a market value equal to but a fraction of the value of the zinc contained in the dross. Any need for an iron or steel container for the bath is eliminated and hence the usual lead cushion is not required. Thus the lead content of the zinc is not increased.

The primary object of the invention is to provide a furnace for melting zinc and other metals

having low melting and oxidation points in which the heating chamber is positioned above the surface of the zinc or other metal, the chamber being sealed against the entrance of air.

A further object of the invention is to provide an apparatus for the purpose specified which facilitates the control of the degree of purity of the bath and the removal of the accumulated impurities.

These and other objects and advantages of the invention will become apparent from a consideration of the drawings and the following detailed specification of practical embodiments of the invention.

In the drawings:

Figure 1 is a top view of a melting furnace constructed in accordance with my invention;

Figure 2 is a sectional view taken along the line 2—2 of Figure 1;

Figure 3 is a sectional view taken along the line 3—3 of Figure 1;

Figure 4 is a cross-sectional view similar to Figure 3 of a modified furnace in which electrical heating elements are substituted for the radiant tubes of Figures 1—3;

Figures 5 and 6 are detailed views of the electrical heating means employed in the furnace of Figure 4;

Figure 7 is a cross-sectional view of a modified form of furnace in which gas flame heating means is substituted for the radiant tube or electrical heating means;

Figure 8 is a cross-sectional view of the gas furnace of Figure 7, the view being taken along the line 8—8 of Figure 7; and

Figure 9 is a top view of another modified form of furnace.

Referring to the drawings, 11 indicates a furnace shell supported in a pit in the concrete foundation 10 and enclosing the inner and outer refractory linings 14 and 12, respectively. A layer of insulating material 13 is positioned between the linings to reduce the heat losses of the furnace. As shown in Figures 2 and 3 the floor of the melting chamber is concaved longitudinally and sloped transversely and portions of the end walls of the chamber are extended at 19 and 21 to provide end walls for a chamber positioned above the surface of the metal being melted or heated. A vertical longitudinally extending wall 18 extends between the walls 19 and 21 adjacent the lowermost section of the floor and divides the metal chamber into a pair of compartments 30 and 31. The lower edge of wall 18 terminates short of the floor of the melting chamber or suitable openings 27 are provided in its lower portion whereby passageways are provided from compartment 30 into compartment 31 along the inclined bottom surface of the chamber.

A second wall 17, parallel with wall 18, spans the compartment 30 and with walls 18, 19 and 21 and a roof forms an air tight enclosure above the surface of the bath of metal in the melting chamber of the surface. The roof consists of a number of refractory plates 22 supported on shoulders on the walls 17, 18, 19 and 21, a layer of insulation 23 above the plates, and a suitable cover 20. The lower edge of wall 17 terminates short of the bottom of the melting pot but it will normally be immersed a considerable distance below the level of the fluid metal. It can thus be seen that the fluid metal itself seals the chamber thus created against the entrance of atmospheric air. Suitable heating means are positioned in said chamber above the level of the fluid metal

and as shown in Figures 1, 2 and 3 the means may take the form of radiant tubes 33, suspended from the roof plates 22 by any suitable means (not shown), and provided with gas burners 39 and 41, in accordance with usual practice. In Figure 4, suitable electrical resistance heating elements 41 are substituted for the radiant tubes 33, which resistance elements are supported from the roof plates 22 on refractory tube carriers 43 suspended from the plates by the rods 42. Bushings 44 are inserted in apertures in the plates to prevent the rods 42 from pulling loose from the plates. Any suitable means may be employed to conduct current to the elements 41.

15 It can thus be seen that the metal of the bath is heated entirely by radiation and since the heating chamber is sealed against the entrance of air, a temperature higher than the ignition point of the metal being heated may safely be maintained in the chamber. This higher temperature results in a higher rate of heat transmission and insures the maintenance of proper conditions in the bath. Since the heat input is readily controlled, the temperature of the bath 20 may be controlled within narrow limits, a feature of importance in galvanizing and other operations. If desired, the heating chamber may be filled with a non-oxidizing or neutral gas and with a pressure slightly higher than atmospheric 25 pressure. To insure against damage to the metal should air accidentally enter the heating chamber and to promote heat conductivity between the chamber and metal, a number of plates 35 of high heat conductivity and impervious to attack by the 30 zinc or other metal being heated are floated on the surface of the metal within the chamber. These plates are preferably of graphite and cover substantially all the surface of the bath within the heating chamber.

35 Figures 7 and 8 illustrate a furnace constructed in accordance with my invention in which a gas flame is substituted for the radiant tubes or electrical heating elements of the furnaces described above. In this embodiment the heater chamber is enlarged and is provided with check-40erwork for the passage of air for combustion and products of combustion. A horizontal wall 50 divides the heating chamber into upper and lower spaces 53 and 54, respectively, each of said 45 spaces being provided with baffles for the circu-50itous passage of the air and the products. The furnace consists of a refractory vessel 46 having a dip tank 47 and a shell 45. In an end wall of the heating chamber, a gas inlet 49 is positioned 55 above the surface of the bath and gas issuing therethrough is adapted to be immediately mixed with air coming into the furnace through a port 57, passing through space 53 and reaching the gas through port 55 in the horizontal wall 50. 60 The products of combustion move across the furnace through space 54 and back again and are exhausted through stack 56. The quantity of air furnished is less than that required for complete combustion of the gas injected so that no oxygen will be available for combination with the metal of the bath. The products of combustion are therefore non-oxidizing and a temperature higher than the ignition point of the metal being heated may be employed. As in the first 65 described embodiments, a plurality of graphite plates 35 are floated on the metal within the heating chamber.

70 Referring again to Figures 2 and 3, it should be noted that the metal of the bath normally comes in contact with no iron or steel other than

that being galvanized. The pump 36 is provided solely to empty the tank and it is arranged for ready removal from the apparatus when not required. When the furnace is first started and pure zinc is placed in the pot and melted, pure zinc may be tapped out of the compartment 31 by removal of the plug 16, allowing the zinc to flow down the spout 15 into the casting bed 38. After a time, however, the impurities in the zinc and some additional iron from the steel being galvanized, if galvanizing is being carried on, will accumulate and settle to the bottom of the bath. Due to the slope of the floor of the bath the impurities will gradually move under the baffle 18 into chamber 31. If plug 16 is now removed the mixture of pure zinc and impurities will rise in the comparatively narrow space 31 and be tapped off. By tapping off small quantities at regularly spaced intervals, the pure portion of the bath can be prevented from dropping below the lower edge of wall 18, the impure zinc can be removed, and additional pure metal may be added. By varying the frequency and quantity of removals, the bath may be operated in such a manner that the purity of the metal is kept at a certain value for galvanizing operations and at the same time the metal tapped off is pure enough to satisfy the requirements for ordinary commercial zinc. The zinc thus tapped off is useful in making castings and for a wide variety of other uses and has a market value only slightly lower than pure electrolytic zinc which is fed to the furnace. It can thus be seen that by reducing metal loss due to oxidation, reducing metal loss due to alloying, and operating the bath in such manner that the impurities may be removed in commercially valuable form, that substantial economies are effected in the operation of the process. Also the heating methods employed result in greater efficiency of the apparatus.

Figure 9 illustrates an installation embodying the features of the invention in which the tank 51 is substantially longer than the tanks 14 of Figures 1-4 and 46 of Figures 7 and 8 to allow a longer path of travel through the bath of the material being galvanized. A plurality of heating chambers 53 and 54, longitudinally aligned, are provided over the surface of the bath and a space 55 is left between them for the convenient insertion of the pump 36. As in Figures 1-3, radiant tubes 33 may be employed in the heating chambers and suitable openings 56 and 58 may be provided in the top wall of the impure metal compartment. In all installations suitable

covers, 57 for example, may be placed over these openings. Figure 9 illustrates that a wide variety of arrangements of the various constituent elements of the apparatus may be made without deviating from the principles of this invention.

As shown more clearly in Figures 1 and 2, the guide 25, the purpose of which is to direct the travel of the material being galvanized (the rods 26, for example), may conveniently be supported at one end on the wall of the dipping compartment and at its other end in the notch 24 provided in the wall 17.

The above specifically described embodiments of my invention should be considered as illustrative only and not as limiting the invention. Various rearrangements and altered combinations of the novel features disclosed are readily apparent and should be taken as being within the scope of the invention if so indicated by the appended claims.

What I claim is:

1. Galvanizing apparatus comprising a refractory lined pot for the support and confinement of a quantity of molten metal, means to heat said metal by radiation, a plate of high heat conductive material floating on the surface of said metal and separating said metal from said heating means, said material being impervious to reaction by the metal, a plurality of compartments in said pot, means to direct the flow of impurities in the metal from one compartment to the other, one of said compartments constituting a vat for the reception of material to be galvanized, and means to tap off the impure metal from the other of said compartments.

2. Galvanizing apparatus comprising refractory surfaces for the support and confinement of a bath of zinc, said surface including an inclined bottom wall and four side walls, a pair of spaced parallel walls extending from above the normal upper surface of said bath toward said bottom wall but terminating short thereof, said parallel walls spanning two opposed walls of said first mentioned walls and spaced from the other two of said first mentioned walls, a plate of high heat conductive material floating on the surface of said bath between said parallel walls, said material being impervious to reaction by said zinc, heating means above said plates, means to guide elongated metal shapes through said bath between one of said parallel walls and one of said four walls and means to tap off zinc from the space between the other of said parallel walls and an adjacent one of said four walls.

FILIP THARALDSEN.
